DESIGN FOR A CLOTHES STICK OR SIMILAR ARTICLE

Elizabeth F. Thomas, Binghamton, N. Y.

Application September 21, 1937, Serial No. 71,700

Term of patent 14 years

To all whom it may concern:

Be it known that I, Elizabeth F. Thomas, a citizen of the United States of America, residing at Binghamton, in the county of Broome and State of New York, have invented a new, original, and ornamental Design for a Clothes Stick or Similar Article, of which the following is a specification, reference being had to the accompanying drawing, forming a part thereof.

I claim:

The ornamental design for a clothes stick or similar article, as shown.

ELIZABETH F. THOMAS.
